US0D1044961S

(12) **United States Design Patent** (10) **Patent No.:** **US D1,044,961 S**
(45) **Date of Patent:** **** Oct. 1, 2024**

(54) **BADGE**

(71) Applicant: **RAZOR USA LLC**, Cerritos, CA (US)

(72) Inventor: **Ian Desberg**, Cerritos, CA (US)

(73) Assignee: **Razor USA LLC**, Cerritos, CA (US)

(**) Term: **15 Years**

(21) Appl. No.: **29/791,879**

(22) Filed: **Feb. 15, 2022**

(51) **LOC (14) Cl.** **12-11**

(52) **U.S. Cl.**

USPC **D21/423; D11/95**

(58) **Field of Classification Search**

(57) **CLAIM**

The ornamental design for a badge, as shown and described.

DESCRIPTION

FIG. 1 is a front perspective view of a badge showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a perspective view of the badge of FIG. 1 shown in a state of use.

The broken lines in the drawings represent portions of the badge that form no part of the claimed design. The broken lines showing a scooter in FIG. 8 represent environmental subject matter only and form no part of the claimed design.

1 Claim, 8 Drawing Sheets
